SUPPORT FOR POTTED PLANTS

Marvin H. Nelson, 4600 Sierrawood Lane,
Pleasanton, Calif. 94566

Filed Oct. 29, 1974, Ser. No. 518,895

Term of patent 14 years

Int. Cl. D6—01, 06

U.S. Cl. D6—182

FIG. 1 is a perspective view of a support for potted plants showing my new design;

FIG. 2 is an end elevational view;

FIG. 3 is a rear elevational view;

FIG. 4 is a bottom plan view.

I claim:

The ornamental design for support for potted plants, substantially as shown.
